US00D881577S

(12) **United States Design Patent** (10) **Patent No.:** **US D881,577 S**
Gibson et al. (45) **Date of Patent:** **** Apr. 21, 2020**

(54) **CARRYING CASE**

(71) Applicants: **Baxalta GmbH**, Glattpark (Opfikon) (CH); **Baxalta Incorporated**, Bannockburn, IL (US)

(72) Inventors: **Madeleine Clare Gibson**, Madison, WI (US); **Seth Dale Jones**, Round Lake, IL (US); **Daniel Edward Roush**, Niles, IL (US); **Nicholas John Schill**, Johnsburg, IL (US); **Ron Theis**, Kewaskum, WI (US); **Denise A. Alexander**, Naperville, IL (US)

(73) Assignees: **Baxalta GmbH**, Glattpark (Opfikon) (CH); **Baxalta Incorporated**, Bannockburn, IL (US)

(**) Term: **15 Years**

(21) Appl. No.: **29/665,385**

(22) Filed: **Oct. 3, 2018**

(51) LOC (12) Cl. **03-01**

(52) U.S. Cl. **D3/318**

(58) **Field of Classification Search**

USPC **D3/232, 245–246, 318**
 CPC **A45C 1/024; A45C 3/06**
 See application file for complete search history.

(57) **CLAIM**

The ornamental design for a carrying case, as shown and described.

DESCRIPTION

FIG. 1 is a top, front, right side perspective view of a carrying case;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The long dash-short dash lines represent the bounds of the claimed design. The dashed lines shown illustrate portions of the carrying case that form no part of the claimed design.

1 Claim, 5 Drawing Sheets
